UNITED STATES PATENT OFFICE.

CLIFFORD V. BATES, OF BARTLESVILLE, OKLAHOMA.

WATCHCASE.

No. 919,117.

Specification of Letters Patent. Patented April 20, 1909.

Application filed October 7, 1907. Serial No. 396,247.

To all whom it may concern:

Be it known that I, CLIFFORD V. BATES, a citizen of the United States, residing at Bartlesville, county of Washington, Oklahoma, have invented certain new and useful Improvements in Watches, of which the following is a specification.

My invention relates to watches.

The object of the present invention is the provision of a watch having novel detachable means whereby it can be readily fastened through a buttonhole, such as the one on the lapel of a man's coat, with the watch proper covered and the watch dial exposed and used, if desired, with any ornamental design or configuration as, for instance, an elk's head, as an emblem.

The invention resides in the combination with a watch having a projecting part on its case formed as a button, and bearing a watch dial, of a detachable member provided with a bezel to engage the said part, one embodiment of the invention being set forth fully hereinafter.

25 The novel features of the invention are recited in the appended claims.

In the accompanying drawings:—Figure 1 is a front view showing a watch dial as it would face the observer when in position on a garment; Fig. 2, a rear view of the watch case; Fig. 3, a side view, showing certain parts, including a part of the head button in section; Fig. 4, a view on line 4—4 of Fig. 3; and Fig. 5, enlarged detail views showing a lug and notch for holding the bezel against rotation.

The watch 1 may contain works of any desired construction, being wound and set by the usual devices 2 and 3. Unlike ordinary 40 watches having an open face which is exposed by opening the lid, the watch has secured to one side of its case a member having a neck 4 and a round head 5 constituting, in effect, a button by which the 45 watch may be buttoned through a buttonhole of the garment, as, for instance, the buttonhole in the lapel of a man's coat. Arbors of the watch pass loosely through the neck and head and are provided with 50 the usual hands 6, while the face of the head has a watch dial 7 used in conjunction with the hands to indicate the time.

At 10 there is shown a bezel which is provided with a crystal 11 and has a lug 12 adapted to take into a notch 13 in the edge 55 of the head 5 to prevent rotation of the

bezel. As the present invention is very capable of use as an emblem, any desired design may be employed in connection with the bezel 10, an elk's head 14 being shown in the present instance as formed integral with or connected to the bezel 10. Obviously other designs could be used. Pivoted on a pin 15 secured to the back of the elk's head 14, or other projection of the bezel 10, is a catch 16 which has an off set finger 17 to take over the edge of the head 5 and lock the bezel on the head, a groove 18 in the part 14 and a projection 19 on the catch 16 snapping into engagement when brought into alinement (permitted by the resiliency of the catch) to lock the catch in the position shown in full lines in Fig. 3 and in dotted lines in Fig. 4. A nib 20 on the catch affords means for its manipulation. 75

The bezel 10 having been removed by swinging aside the catch 16 to the position shown in full lines in Fig. 4, the button 5 can be passed through the buttonhole of a coat and the bezel thereafter engaged with the head and locked by the lug 12 and catch 16 whereupon the elk's head 14 or other design and the watch dial will be located on the outside of the lapel and the watch 1 will be covered by the lapel. 85

The device constitutes a regular time piece from which the time may be readily ascertained by inspection.

I am aware that the present invention could be put to different uses from those specified, the designs changed, and the manner and construction of attachment of the parts altered without departing from the spirit and scope of the invention and all such variations are, therefore, intended to be comprehended within the claims. 90

Having thus described my invention, what I claim as new, and desire to secure by Letters Patent is:—

1. The combination with a watch having a projection provided with a watch dial on its end, and hands operated through the projection and playing over the dial, of a bezel detachably engaged with said projection and a swinging catch carried by the bezel to engage the projection and lock the bezel thereon. 100

2. The combination with a watch having a projection provided with a round end, and having a dial on its face, of hands playing over the dial and operated from the watch through the projection, a round bezel de- 105

tachably engaging said round end of the projection, and a catch carried by the bezel adapted to engage with the round end of the projection to secure the bezel thereto.

5 3. The combination with a watch dial having a projection provided with a round end, and having a dial on its face, of hands playing over the dial and operated from the watch through the projection, a round bezel
10 engaging the round part of the projection, a lug and notch connection between the

bezel and round part of the projection preventing rotation of the bezel, and a releasable catch carried by the bezel and engageable with the round part of the projection. 15

In testimony whereof, I hereunto affix my signature in presence of two witnesses.

CLIFFORD V. BATES.
